5 Claims. (Cl. 60—97)

This invention relates to compressors, and more particularly to an air compressor powered by pressurized hydraulic medium for use in a motor vehicle.

The motor vehicle of today is becoming more dependent upon power driven units, or accessories, for the operation, or remote control, of various assemblies incorporated in the vehicle, such as a power steering arrangement, and also such accessories as power operated windshield wiper motors, windows, folding tops, and seat positioners, to mention but a few. The power system for operating such units may be electrical, hydraulic, or pneumatic.

In those vehicles having a power steering arrangement utilizing pressurized hydraulic medium as a power source, a pump means for the pressurization of such hydraulic medium may be arranged for power take-off from the engine, for example, by way of the fan belt. The power steering arrangement in such a system may be designed to supply torque for vehicle steering only under certain conditions, such as where a torque of a predetermined amount has been applied to the steering wheel of the vehicle. Such power steering arrangement automatically circulates the pressurized hydraulic medium therethrough without development of turning torque when the aforementioned conditions are not present, that is, when torque development by the medium for steering is uncalled for during motor vehicle operation.

The present invention serves as a means for development of a source of compressed air to be used in the operation of certain air powered units in a motor vehicle. A compressor, representative of an embodiment of the invention, is so arranged in a circuit for utilization of a source of pressurized hydraulic medium for the compression of air, when such hydraulic source is not being utilized by the power steering arrangement of the vehicle. To put it another way, the compressor of the invention is arranged in a circuit for utilization of pressurized hydraulic medium during those periods when such medium is not being called for by the power steering arrangement for development of turning torque. The pressurized hydraulic medium, instead of circulating freely through the power steering arrangement without development of turning torque, may be automatically diverted to the compressor for compression of air, which is directed to a storage tank to be drawn off by the various air operated units as required.

The main object of this invention is to provide an air compressor for use in a motor vehicle, which compressor is powered by pressurized hydraulic medium.

Another object of the invention is to provide a compressor for use in a motor vehicle which utilizes a source of pressurized hydraulic medium when such medium is not being called for by another unit, or accessory, of the motor vehicle.

A further object of the invention is to provide a system including the device of the invention, in which a source of pressurized hydraulic medium is utilized for operation of multiple units in the motor vehicle but with certain of these units given a preference over others in a predetermined manner.

Another object of the invention is to provide a system in a motor vehicle, which system includes a hydraulically powered air compressor arranged to utilize pressurized

2

hydraulic medium when such medium is not required by a power steering arrangement in the vehicle.

A further object of the invention is to provide an air compressor in a motor vehicle which utilizes a source of pressurized hydraulic medium for air compressor operation when such medium is not being utilized by another unit in the vehicle, said system being further arranged for termination of compressor operation when air has been compressed in a storage tank to a predetermined degree whereupon the medium is redirected to the other unit.

These and further objects and features of the invention will become more apparent from the following description and the accompanying drawings wherein:

FIG. 1 is a fragmentary perspective view of a motor vehicle illustrating the device of the invention applied to the vehicle;

FIG. 2 is a top plan view of a pilot valve block used in the device of the invention;

FIG. 3 is a side view of same;

FIG. 4 is a bottom plan view of same;

FIG. 5 is a section view as seen from line V—V in FIG. 2;

FIG. 6 is a plan view of the device of the invention;

FIG. 7 is a section view as seen from line VII—VII in FIG. 6;

FIG. 8 is a view as seen from line VIII—VIII in FIG. 7;

FIG. 9 is a view as seen from line IX—IX in FIG. 7;

FIG. 10 is a section view of a solenoid operated valve mechanism used in connection with the device of the invention;

FIGS. 11, 12, 13 and 14 are schematic representations of the device of the invention illustrating the relative position of certain parts during operation; and

FIG. 15 is a schematic diagram illustrating a modified manner in which the compressor of the invention may be connected to complementary units included in the system of the invention.

Referring to the drawings, and more particularly to FIG. 1, numeral 16 identifies a motor vehicle having an engine 17, and a battery 18 installed therein in the usual manner; and a steering mechanism 19, including a power steering assembly 21, having a distributing valve 20 which automatically directs hydraulic fluid flow for development of turning torque under certain conditions of vehicle steering, as is well known to those skilled in the art. A hydraulic pump unit 22, arranged for power take-off from an engine as illustrated by use of a fan belt 23, is adapted for the pressurization and circulation of hydraulic fluid, such as oil, to the power steering assembly 21. The latter is so arranged as to utilize the pressurized hydraulic fluid for generation of torque as required by the steering mechanism for power steering, and is further arranged for the by-passing of the pressurized hydraulic fluid when torque is not required by the steering mechanism. A circuit for conduction of hydraulic fluid between the pump unit 22 and the power steering assembly 21, includes certain conduits, or hoses, as will be identified later herein.

Positioned within the motor vehicle is a compressed air storage tank, or reservoir, 25 which serves as a source of compressed air supply for pressure operated units, such as a fluid pressure operated wiper motor 24, connected to the reservoir by a conduit, or hose 26. A solenoid-operated hydraulic valve assembly 27 is interposed in the hydraulic circuit leading from the pump units 22 to the power steering assembly 21. A hydraulically operated compressor 28, representing an embodiment of the invention, is connected to the steering assembly 21 and the reservoir 25, by conduit, or hose means, in a manner which will be described in detail hereinafter.

As best seen in FIGS. 2—9, the compressor 28 includes

a hydraulic portion 29 and a pneumatic portion 31, said portions being joined by fastening means, such as screws 32. A compound piston assembly 33 is adapted for reciprocating motion in said portions, and more specifically has piston heads 34 for reciprocating movement solely in a piston chamber 30 formed in the hydraulic portion 29, and a piston head 36 arranged for reciprocating motion solely within a piston chamber 35 formed in the pneumatic portion 31. The piston heads 34 are adapted for reciprocating movement as a result of hydraulic pressure being alternately applied thereagainst, which movement is transmitted to the piston head 36 for compression of air in the pneumatic portion.

The hydraulic portion includes a cylinder housing 37, having an integral flange 38 at one end for connection with the pneumatic portion 31, a valve block 39, and a valve housing 41. The valve block 39 is arranged between the valve housing 41 and a valve head portion 42 formed on the cylinder housing 37. The piston heads 34 are arranged to divide the piston chamber 30 into three volumes 43, 44 and 46, volume 43 being of fixed size, while volumes 44 and 46 are of variable size depending upon the position of the piston assembly 33 within the piston chamber 30. A piston valve head 47 is affixed to the end of the piston chamber 30 by fastening means such as screws 48.

The pneumatic portion 31 includes a cylinder 49 affixed to the flange 38 by the screws 32, and a cylinder head 51 which is affixed to the cylinder by fastening means such as screws 52. Air intake passageway 53 formed in the cylinder 49 extends between a poppet valve 54, arranged in the flange 38, and a poppet valve 56 arranged in the cylinder head 51. Diametrically opposite passageway 53 is an air exhaust passageway 57, which extends between a chamber 58, containing a poppet valve 59, and a chamber 61, containing a poppet valve 62. Each of the poppet valves has a compression spring to urge the poppet valve toward cylinder 49 for regulation of air flow into and out of the piston chamber 35, as will be explained in further detail. A threaded recess 63 is arranged for reception of a conduit, or hose, 64 connecting the air intake passageway 53 with an air strainer 66, while a threaded recess 67 is arranged for reception of a conduit, or hose 68 the other end of which connects with the reservoir 25.

The valve housing 41 has a cylindrical chamber 69, with the longitudinal axis thereof arranged parallel to that of the piston chamber 30, in which is arranged for reciprocable motion a reversal, or spool valve, 71. The spool valve has four pistons 72, 73, 74 and 76 arranged to provide volumes 77, 78, 79, 81 and 82; volumes 78, 79, and 81 are of fixed size, whereas, volumes 77 and 82 are of variable size depending upon the position of the spool valve 71 in the chamber 69. At each end of the chamber 69 is a threaded plug 83 for closing the ends of said chamber. A boss 84, projecting from the exterior top surface of the valve housing 41, has a threaded opening 86 for reception of a conduit, or hose, 87 the other end of which is affixed to the hydraulic valve assembly 27. Extending from the threaded opening 86 is a passageway 88 which opens into the mid-point of the chamber 69. It is to be noted that the spool valve 71 has end projections 89 for abutment with an adjacent threaded plug 83, to thus fix the minimum size of volumes 77 and 82.

The valve block 39 has a cylindrical chamber 91, with the longitudinal axis thereof perpendicular to that of the cylindrical chamber 69, and a pilot valve 92, reciprocably arranged within chamber 91. Threadably affixed at each end of the chamber 91 is a threaded plug 93. The pilot valve has pistons 94, 96, 97 and 98 which are arranged to provide volumes 99, 101, 102, 103, and 104 in the chamber 91, volumes 101, 102 and 103 being of fixed size, while volumes 91 and 104 are of variable size depending upon the position of the pilot valve within the chamber. At each end of the pilot valve are projections 106, for

abutment with an adjacent threaded plug 93, to thus establish the minimum size of volumes 99 and 104.

A plurality of passageways, arranged between the various units comprising the hydraulic portion, are best described with reference to FIG. 11. Passageways 107 and 108, opening into the chamber 69 in the region of volumes 78 and 81 respectively, extend from the housing 41, through the valve block 39 and into a horizontal passageway 109, formed in valve head portion 42; a vertical passageway 111 connects with passageway 109 and opens into the piston chamber 30 at the mid-portion thereof. Passageways 112, 113 and 114, open into the chamber 69 in the region of the mid-portion thereof. Passageway 112 extends through the valve block 39 and leads to and opens into one end of the piston chamber 30, in the region of volume 46; passageway 114 extends through the valve block 39 and leads to and opens into the other end of the piston chamber 30, in the region of volume 44; and passageway 113 leads to and opens into the mid-portion of the cylindrical chamber 91. It will be seen that when the spool valve 71 is in extreme left position (FIGS. 7 and 11) in the chamber 69, passageways 88, 112, and 113 will be in communication with volume 79, while passageways 114 and 108 will be in communication with volume 81, 25 and passageway 107 will be in communication with volume 78. When the spool valve 71 is positioned at the opposite end of the chamber 69, as in FIG. 12, passageways 113, 114 and 88 will be in communication with volume 79, passageways 112 and 107 will be in communication with volume 78, and passageway 108 will be in communication with volume 81.

Passageway 116 opens into the end of chamber 69 in the region of volume 77, and its other end leads to and opens into a mid-portion of the chamber 91; passageway 35 117 opens into the opposite end of the chamber 69 in the region of volume 82, and leads to and opens into the mid-portion of the chamber 91. Passageways 118 and 119, opening into the chamber 91 in the region of volumes 101 and 103 respectively, are connected to a passageway 40 121 which is in communication with horizontal passageway 109. Passageways 122 and 123, opening into the chamber 91 in the region of volumes 104 and 99 respectively, lead to and open into the piston chamber 30 in the mid-portion thereof.

It will be seen that when the pilot valve is positioned toward the right end of the chamber 91 (FIG. 11), passageways 113 and 117 will be in communication with volume 102, passageways 116 and 118 will be in communication with volume 101, and passageway 119 will be in communication with volume 103, when the spool valve is positioned at the opposite end of the chamber 91, (FIG. 12) passageways 113 and 116 will be in communication with volume 102, while passageways 117 and 119 will be in communication with volume 103, and passageway 118 will be in communication with volume 101. A threaded recess 124, arranged for reception of a conduit, or hose, 126 is located at the mid-portion of the piston chamber 30 to connect volume 43 with a conduit, or hose, 127 arranged for return flow of hydraulic medium to the pump unit 22.

Referring to FIGS. 1 and 10, the hydraulic valve assembly 27 includes a threaded recess 128 for reception of a conduit, or hose, 129 connected to the pump unit 22, a threaded recess 131 for reception of the hose 87 connected to the compressor 28, and a threaded recess 132 for reception of a hose 133 leading to the power steering assembly 21. The valve assembly 27 has a solenoid 134 arranged for the shifting of a spool valve 136, for the interconnection of conduits 129 and 133 to allow flow of hydraulic fluid from the pump unit 22 to the power steering assembly 21, and also includes a compression spring 137, which shifts the spool valve when the solenoid 134 is inactivated, so that connection is made between conduits 129 and 87 for flow of hydraulic fluid from the pump unit 22 to the compressor 28.

A solenoid controlled valve 138, connected to ignition switch 139 is located in the conduit 26 extending between the reservoir 25 and the wiper motor 24. The valve 138 permits the pneumatic circuit between the reservoir and wiper motor to be opened when the ignition is turned on; spring means (not illustrated) arranged in the valve 138 closes the valve when the ignition is turned off, so that leakage of air from the reservoir through the wiper motor is prevented when the vehicle is not in operation.

A pressure operated electrical switch 141 is mounted upon the reservoir 25, which switch is responsive to a predetermined pressure in the reservoir to activate the solenoid 134 of the valve assembly 27, to thus discontinue operation of the compressor 28, by diverting hydraulic fluid to the steering assembly 21, when the pressure in the reservoir attains said predetermined amount. A switch means 142, is responsive to movement of the distributing valve 20, to complete the circuit through the solenoid 134 of the valve assembly 27, and thus direct hydraulic fluid to the steering assembly 21, for development of turning torque.

The operation of the compressor 28 will now be described.

Referring to FIG. 11, the position of the movable parts of the compressor are shown during operation, with the piston assembly 33 moving in the direction of the cylinder head 51. For purposes of clarification, arrows have been used in the illustration to indicate the type and direction of fluid flow in the passages and chambers, viz., single-headed arrows indicate air flow under atmospheric pressure, double-headed arrows indicate pressurized air flow, and triple-headed arrows indicate flow of pressurized hydraulic medium, such as oil, coming from the pump unit 22 via valve assembly 27.

Pressurized hydraulic medium entering the compressor through hose 87, passes through the passageway 88 into volume 79 of the spool valve 71, and into passageway 112 to piston volume 46, to exert a force upon the piston assembly 33, thereby causing motion of piston head 36, resulting in compression of air in piston chamber 35, which flows from the piston chamber, past poppet valve 62 into air exhaust passageway 57, and hose 68. As the piston head 36 is moving within the piston chamber 35, the poppet valve 54 will be unseated to allow flow of air under atmospheric pressure into the piston chamber on the side of the piston head opposite to which compression is taking place. The pressure of hydraulic fluid in volume 79 is transmitted through passageway 113, volume 102 of the pilot valve 92, through passageway 117, into variable volume 82, to act against piston 76 of the spool valve 71, while simultaneously the variable volume 77 is open to the exhaust 127 leading to the inlet of pump 22 via passageway 116, volume 101, passageway 118, passageways 121, 109, 111, and piston volume 43. The pressure differential thus established upon the spool valve 71 is effective to maintain the latter in the position illustrated.

When the piston assembly 33 has neared the end of its movement, as above described, the end of passageway 122 will be uncovered by a piston head 34, resulting in the connection of passageway 122 to volume 46, as illustrated in FIG. 12. Immediately upon such action, pressurized hydraulic medium will flow from passageway 122 into variable volume 104 of the pilot valve 92, to exert a pressure upon piston 98, resulting in the shifting of the pilot valve to the other end of the chamber 91, as illustrated in FIG. 12. Variable volume 99, being connected to the exhaust hose 127 via passageway 123, and piston volume 43, results in the establishment of a pressure differential between the ends of the pilot valve, resulting in the movement thereof. As soon as such movement of the pilot valve occurs, hydraulic flow in passageway 113 will be directed to passageway 116 via volume 102, to the variable volume 77 resulting in pressure against the piston 72. Simultaneously, the hydraulic fluid in variable volume 82 will be released to the exhaust hose 127

via passageway 117, volume 103, passageways 119, 121, 109, and 111, through piston volume 43. As a result of pressure differential thus established on the spool valve 71, movement of the spool valve will take place toward the opposite end of the chamber 69. In such position of the spool valve, it will be seen that pressurized hydraulic fluid will pass from the volume 79 into passageway 114, and into variable piston volume 44 to act against piston head 34, and at the same time piston volume 46 will be open to the exhaust hose 127 via passageway 112, volume 78, passageways 107, 109 and 111, and through piston volume 43. As a result, movement of the piston assembly 33 will commence in a reverse direction as illustrated in FIG. 13.

Such movement of the piston assembly 33 will result in the compression of air in the piston chamber 35 between the piston head 36 and the flange 38, resulting in the unseating of poppet valve 59 and the flow of compressed air into chamber 58 and exhaust air passageway 57 to the hose 68. During such movement of the piston assembly, air under atmospheric pressure will flow in the passageway 53, past poppet valve 56, and into the piston chamber 35 on the side of the piston head opposite to that on which compression of air is taking place.

Movement of the piston assembly in such direction will continue until a piston head 34 uncovers the end of passageway 123. When this occurs, pressurized hydraulic medium will flow through passageway 123, into volume 99 of the chamber 91 to exert pressure against the piston 94. At the same time, the variable volume 104 will be connected to the exhaust hose 127 via passageway 122, and piston volume 43, thus resulting in movement of the pilot valve to the opposite end of the valve chamber 91, as illustrated in FIG. 14. In such position, the pilot valve

will establish connection of the passageway 113 with passageway 117 via volume 102, resulting in hydraulic fluid flow into variable volume 82 of the spool valve 71. At the same time, variable volume 77 will be connected with the exhaust hose 127 via passageway 116, volume 101, passageways 118, 121, 109, and 111, through piston volume 43. The spool valve 71, as a result of pressure differential established between pistons 76 and 72, will be shifted to the other end of the chamber 69. In this position of the spool valve, hydraulic pressure fluid will flow from volume 79 into passageway 112, and thence into piston volume 46 to act against piston head 34, while at the same time, variable volume 44 will be connected to exhaust hose 127 via passageway 114, volume 81, and passageways 108, 109, 111, and volume 43. As a result of the pressure differential acting upon the piston heads 34, movement of the piston assembly will commence in the opposite direction, to thus cause compression of air in the piston chamber 35, between piston head 36 and cylinder head 51.

It may be stated that the poppet valves are each spring loaded to permit unseating of each poppet valve in a predetermined manner. More particularly, the spring of poppet valves 54 and 56 are of such strength as to allow unseating of the valve under the pressure differential established between the exterior atmospheric pressure and the interior sub-atmospheric pressure existing in the cylinder, while the springs of poppet valves 59 and 62 are adapted for unseating of the poppet valves when the pressure differential between the air within the cylinder and the air in the volumes of chamber 58, passageway 57, and hose 68 has risen to a predetermined amount.

The circuit arrangement illustrated in FIG. 15, differs from the circuit arrangement described above primarily in the use of a hydraulically pressure operated valve 146 in place of the hydraulic valve assembly 27 which is a solenoid controlled type of valve. For simplification, in the following description, the elements identical with those described above, have been given the same numerals. A second valve 147 is arranged for connection to the distributing valve 20 in such a manner that movement of the

distributing valve 20 will cause movement of a piston 148 slidably arranged in the valve 147. As shown in FIG. 15, the piston 148 of valve 147 is in a neutral or non-operative position, which occurs when the power-steering assembly 21 is not utilizing oil for development of turning torque. It will be seen that in such position of the piston 148, oil from the pump 22, flowing in a hose 149, will enter the valve 146 between piston heads 151 of a piston 152, from whence it will flow into a hose 153 connected to the compressor 128 for operation of the compressor. At the same time, oil will enter the hose 154 which is connected to the movable portion of the valve 147, said oil flow in hose 154 entering the valve between piston heads 156 of the piston 148, such flow ending when the volume between piston heads 151 is completely filled by the oil.

When oil is required for development of turning torque in the power-steering assembly 21, the distributing valve 20 will shift, resulting in movement of the piston 148 toward one or the other end of the valve 147, depending upon the direction of vehicle steering. Such movement of the piston 148 will cause oil flow from hose 154 into the volume defined by the piston heads 156, and then into hose 157. The hose 157 is connected at the other end to the lower part of the valve 146 in a region below the bottom piston head 151, whereby oil flow from hose 157 will cause upward movement of the piston 152. As a result thereof, oil flow from hose 149 will be shut off from hose 153 and instead will be directed into hose 158, the opposite end of which connects with the distributing valve 20. Such oil flow into the distributing valve 20 will be directed into pipe 159 or 161, for development of turning torque in the power-steering assembly for turning in a right or left direction accordingly. Upon completion of the vehicle turning operation, that is, when pressurized oil is no longer required for development of turning torque, the distributing valve 20 will move so that the piston 148 will be returned to its neutral position (FIG. 15). It will be seen that when the piston 148 returns to neutral position, the oil entrapped under the lower piston head 151 may flow through hose 157 into the valve 148, through a volume defined by one of the piston heads 156 and a piston head 162 into a hose 163 which joins with a hose 164 provided for the return flow of oil from the distributing valve 20 back to the oil pump 22. Movement of the piston 152 downwardly is effected by a helical spring 166 arranged at the top end of the piston 152, which spring is compressed during upward movement of the piston.

A hose 167 connects the compressor 28 to the reservoir 25, while a hose 168 connects the reservoir to the lower end of the valve 146. A release valve 169 is adapted to allow flow of compressed air into the hose 168 when pressure in the reservoir attains a predetermined value, said release valve being further arranged for venting of the hose 168 to atmosphere when the release valve is in closed position. It will be seen that compressed air flowing from hose 168 into the valve 146, will act upon a piston 171 to move the latter upwardly into abutment with the piston 152, to cause movement of the piston 152 upwardly, so that oil flow in hose 149 will be continued in hose 158, while flow of oil into the hose 153 will be cut off. In such manner, operation of the compressor 28 will stop when compressed air pressure in the reservoir attains a predetermined value. Oil flow thus directed into hose 158, passes through the distributing valve 20 and into hose 164, such oil flow continuing until the distributing valve 20 is fixed for directing of oil into pipes 158 or 161 for development of turning torque, or until pressure in reservoir 25 drops below the predetermined value as determined by the setting of the release valve 169. When air pressure in the reservoir drops below the predetermined value, the release valve 169 will be closed, hose 168 will be vented to atmosphere, piston 171 and 152 will be moved downwardly in the valve by action of spring

166, and oil flow will again occur from hose 149 into hose 153 to cause operation of the compressor 128.

From an understanding of the foregoing, it will be seen that the compressor of the invention may be connected to the oil pump 22 and the power-steering assembly 21 for operation regulated by a hydraulically pressure operated valve 146, the action of which is controlled by a valve 147 responsive to movement of the distributing valve 20 of the power-steering assembly 21.

10 The foregoing description has been given in detail for clearness and without thought of limitation since the inventive principles involved are capable of assuming other physical embodiments without departing from the spirit of the invention and the scope of the appended claims.

15 What is claimed is:

1. In a motor vehicle, the combination including a power-steering arrangement utilizing pressurized hydraulic medium for development of turning torque under certain conditions of vehicle steering, an air compressor having operating means powered by the pressurized hydraulic medium, a reservoir coupled to the compressor for the storage of compressed air, a valve means for directing pressurized hydraulic medium alternatively to the power-steering arrangement and to the operating means of the air compressor, said valve means when in non-operative position directing said medium to the operating means of said air compressor and when in operative position directing said medium to the power-steering arrangement, switch means actuated by the power-steering arrangement for establishing said operative position of said valve means, and a pressure responsive means establishing said operative position of the valve means when air pressure in the reservoir rises to a predetermined value.

2. In a motor vehicle having a source of pressurized hydraulic medium, the combination including a power-steering arrangement having control means directing hydraulic medium within the power-steering arrangement for development of turning torque under predetermined conditions of vehicle steering, said control means allowing the bypass of pressurized medium in the absence of said conditions of vehicle steering, an air compressor having operating means powered by pressurized medium, a reservoir coupled to the compressor for the storage of compressed air, a valve having an operative position for direction of pressurized medium to the power-steering arrangement, said valve having a non-operative position in which pressurized medium is directed to the operating means of said air compressor, and pressure operated means establishing said operative position of said valve means when air pressure in the reservoir rises to a predetermined value.

3. In a motor vehicle, the combination including a power-steering arrangement utilizing pressurized hydraulic medium for development of turning torque under certain conditions of vehicle steering, an air compressor having operating means powered by pressurized hydraulic medium, a reservoir coupled to the compressor for the storage of compressed air, a solenoid operated valve alternatively directing pressurized hydraulic medium to the power steering arrangement and to the operating means of said air compressor, said valve having a non-operative position directing said medium to the operating means of said air compressor and an operative position in response to switch means associated with the power steering arrangement directing said medium to the power steering arrangement, and a pressure operated switch means on the reservoir energizing the solenoid valve for movement to operative position when air pressure in the reservoir rises to a predetermined value.

4. In a motor vehicle, the combination including a power-steering arrangement utilizing pressurized hydraulic medium for development of turning torque under certain conditions of vehicle steering, an air compressor having operating means powered by pressurized hydraulic medium, a reservoir coupled to the compressor for the

storage of compressed air, a first valve means having a piston normally positioned for directing pressurized hydraulic medium to the operating means of said compressor, said piston being movable for direction of pressurized hydraulic medium to the power-steering arrangement, a second valve means responsive to the power-steering arrangement and having a piston movable to direct pressurized medium for movement of the piston in the first valve means, said second valve piston being movable during utilization of pressurized hydraulic medium by the power-steering arrangement, and means including a conduit between said reservoir and the first valve means for movement of said first valve piston when the compressed air pressure in the reservoir attains a predetermined value.

5. In a motor vehicle, the combination including a power-steering arrangement utilizing pressurized hydraulic medium for development of turning torque under certain conditions of vehicle steering, an air compressor having operating means powered by pressurized hydraulic medium, a reservoir coupled to the compressor for the storage of compressed air, a valve means for selectively directing pressurized hydraulic medium to one of the

power-steering arrangement and the operating means of said air compressor, said valve means when in one position directing said medium to the operating means of said air compressor and when in another position directing said medium to the power steering arrangement, switch means responsive to the power steering arrangement to hold the valve means in said other position, and a pressure responsive means establishing said other position of the valve means when air pressure in the reservoir rises to a predetermined value.
